45 Claims. (Cl. 139—134)

This invention involves an apparatus and a method for the electro-dynamic propulsion of a body in a rectilinear path or along and between the limits of a defined path or into space.

5 In various types of mechanisms and for various purposes it is desirable to produce, or conversely to retard, a given translatory velocity in a body from or to rest rapidly with a minimum of mechanical shock and jar upon the body itself 10 and upon the mechanism producing the movement of the body. The desired translatory movement may be along a rectilinear path or along any other defined path within limits or may result in the projection of the body into space or in 15 the retardation of the body arriving from space. It requires a very carefully designed and constructed mechanism even to approximate these desirable results because the mechanical device is subjected to much wear and requires frequent 20 adjustment and because, as a practical matter, it is quite impossible by mechanical means satisfactory to eliminate the shock occasioned by rapid acceleration or deceleration of a body.

The present invention has for its object to provide 25 an electro-dynamic apparatus operable to exert a unidirectional force upon a body within the influence of the magnetic field created thereby.

The object of the invention is further to provide 30 an electro-dynamic apparatus operable to project a body into space.

The object of the invention is further to provide 35 an electro-dynamic apparatus operable to exert a unidirectional force upon a body along a defined path and between defined limits.

35 The object of the invention is further to initiate and rapidly to accelerate or decelerate translatory movement of a body by electro-dynamic means.

The object of the invention is further to provide 40 an electro-dynamic apparatus for initiating, accelerating and projecting therefrom a body placed within the magnetic field created thereby.

The object of the invention is further to provide 45 in a loom an electro-dynamic apparatus operable to effect translatory movement of one of the loom elements.

The object of the invention is further to provide 50 in a loom an electro-dynamic apparatus operable to pass the filling through the shed.

50 The object of the invention is further to provide in the loom an electro-dynamic apparatus for propelling, for checking, or for both propelling and checking a filling carrier of any type transversely of the shed.

55 These and other objects and features of the

invention will appear more fully from the accompanying description and drawings and will be particularly pointed out in the claims.

An apparatus embodying the invention and carrying out the method of the invention consists essentially of an electro-magnetic system arranged to produce a useful, magnetic field distributed along a rectilinear or other defined terminated path and a body movable relatively thereto within the field acted upon electrodynamically by a unidirectional force tending to move it along or parallel with the said path and to project it from the field. In the application of the invention herein to be described, the electro-magnetic element is illustrated as the stationary 10 one and is termed a "stator", while the element electrodynamically acted upon is illustrated as the movable one and is termed a "translator". But the broad principles of the invention apply whichever of the two elements is the stationary 15 one and the other the movable one.

The broad principle involved in this invention is that the force acting upon the translator is created by the natural law which governs when an electrical conductor in which current is flowing is located within a magnetic field. Under these conditions a force acts upon the conductor which tends to move it in a direction cutting the 20 lines of force or flux of the field.

The present invention involves a novel adaptation of this broad principle and provides an electro-magnetic field created by a polyphase electric current with the exciting coils placed upon a core in a manner to create a field varying in 30 intensity and in which the point of maximum 35 flux density travels rectilinearly or between the limits of a defined path. Such a field, when acting upon an electric conductor, generates or induces a current therein and this induced current flowing in the conductor coacts with the flux of 40 the field to set up a force thereon tending to cause the conductor to move with the traveling field and with rapid acceleration to attain a speed approximating that of the field itself. As 45 a result of this relation of elements, an instrumentality is created by means of which an electric conductor free to move and placed within the field will be set in motion along or parallel with the direction of travel of the field, and will at the limit of the path of the field be projected 50 from the field into space.

It has been stated previously that the apparatus creates a unidirectional force on the translator. By the use of the term unidirectional, it is intended to define the characteristics of the 55

apparatus which cause it to exert its total electro-dynamic force on a body placed within its field in a given direction when the apparatus is connected electrically in a given manner. The same apparatus by changing the electrical connections, however, may be caused to exert a force in the opposite direction.

The same electro-dynamic apparatus consisting of stator and translator may be used also to produce deceleration upon the translator. There are several practical methods of accomplishing this result as follows. Obviously, if the electrical connections to the coils which produce the traveling field used for producing acceleration be altered so that the field travels in the opposite direction, a force in the opposite direction will be produced upon the translator. The translator may be decelerated, therefore, by subjecting it to a magnetic field traveling in a direction opposite to that of its movement.

The above method of decelerating the translator contemplates the use of polyphase alternating current. Single phase alternating current correctly applied to any or all of the coils will produce a magnetic field varying in intensity, but not traveling rectilinearly. Such a field may be employed to decelerate the translator. In general if the translator be moved through such a field, its velocity is checked by the damping action of the eddy currents set up in the translator by the stationary oscillating field created by the single phase current.

A third and possibly the most desirable method of checking the translator is by the use of direct current. If direct current is applied correctly to any or all of the coils, a stationary magnetic field is created. If the translator be moved through this field, its velocity is checked by the damping action of the eddy currents set up in the translator which coact with the stationary field.

The stator and translator elements may be correlated in any desirable manner, depending upon the efficiency desired and the particular function to be secured. The apparatus is of wide application and may be used in any situation where it is desired to produce translatory motion along a defined terminated or restricted path between limits or to project a body into space or to cause it to travel along a predetermined path under its own momentum.

As one of the many specific embodiments of the principles of the broad invention, an application of the invention to performing certain functions in the operation of a loom is set forth herein. This embodiment of the invention also in itself involves broad additional features of novelty. While an apparatus embodying the invention is useful for producing various functions in the operation of a loom, it is particularly advantageous in the carrying of the filling through the shed during the weaving operation.

In a loom, the filling must be passed through the shed of warps in order to form therewith the cloth being woven. This filling may run continuously back and forth, it may be inserted in single or double picks or otherwise, the supply of filling may be carried bodily through the shed or it may be taken from a supply located outside of the shed, but in all cases a translatory motion in a defined limited path, usually rectilinear, rapidly repeated, is necessary. In the ordinary type of loom utilizing a shuttle carrying the supply of filling, which is here selected for illustrating a preferred embodiment of the invention, it is usual to employ a mechanically-operated picker

stick at each side of the loom and to vibrate these picker sticks by a cam mechanism, thus to pick the shuttle back and forth through the shed. This type of picker mechanism is unsatisfactory because it essentially involves a high degree of noise and vibration, with many undesirable results.

The present invention enables the required velocity to be given to the shuttle or other filling carrier with an entire absence of shock and jar, noise and vibration and also enables the movement of the shuttle or the filling carrier to be checked in the same manner. Thus a loom may be designed to function with great efficiency and high accuracy due to the embodiment of the present invention therein.

In the drawings, a simple type of loom is shown and translatory device of the invention is shown as embodied in a filling carrier of the shuttle type. Since in the disclosure of a preferred form of the present invention as embodied in a loom, it is only necessary to consider an apparatus for and method of propelling and checking this shuttle or filling carrier, it is unnecessary either to illustrate or describe other features of a loom construction and operation. Such features all may be of any desired type. It is unnecessary even to disclose mechanisms such as a protector mechanism, stop motion mechanisms, or mechanisms for changing the operation of the loom which are commonly associated with or controlled by the filling or the filling carrier as such mechanisms in themselves form no part of the present invention and may be of any type and may be adapted to a loom embodying the present invention if and as desired.

Fig. 13 is a diagrammatic plan view illustrating an application of the invention to the propulsion of a translator having a thin fin in a defined terminated path.

The apparatus herein disclosed as a preferred embodiment of the invention in connection with a loom for propelling a shuttle through the shed

and for checking the movement of the shuttle is shown in duplicate at each end of the lay, the construction being the same in each case. The apparatus comprises a core of two rectilinear laminated soft iron or steel sections of a length sufficient to produce the proper impulse upon the shuttle. These two core sections are held in spaced relation to form an air gap by means of a supporting framework preferably designed to avoid undesirable dispersion of the flux from the air gap. One of the core sections is slotted to receive the exciting coils. The assembled unit which constitutes the stator is mounted lengthwise at the end of the lay preferably with the coils in the lower core section.

The effective translator travels rectilinearly in the air gap between the core sections. Electrical efficiency requires minimization of the reluctance to the magnetic flux across the air gap and the electro-dynamic efficiency requires that the translator moving in the gap shall have as high an electrical conductivity as possible to permit the flow of induced currents therein. The efficiency of the translatory operation also depends upon the weight of the translator or body to be moved. While, therefore, satisfactory results may be secured with any reasonable width of air gap by providing a composite or laminated translator both of highly electrically-conductive material to carry the induced current and of highly magnetic material to transmit the magnetic flux and thus in effect to reduce the air gap, the best results are secured by providing as thin an effective translator as possible of electrically-conductive material and consequently a narrow air gap. The term "electrically-conductive body" as applied to the translator herein, unless otherwise qualified, is of broad significance and includes either a simple or composite body, provided it has the capacity of having induced therein by the magnetic flux the currents necessary for the functioning of the apparatus.

If the effective translator is to carry with it a load of substantial bulk, such as a shuttle body and a supply of filling, then it is desirable that the thin plate or fin of electrically-conductive material constitute the translator traveling in the air gap between the core sections while the load is carried by the shuttle body outside of the core sections.

In the construction illustrated in Figs. 1 to 6 of the drawings, the shuttle is shown as designed to carry a bobbin containing the yarn supply. The body portion of such a shuttle may be formed of any suitable material and the effective translator is in the form of a fin or thin plate of electrically-conductive material, such as aluminum, projecting laterally therefrom. This fin may be secured to the shuttle body or the entire shuttle, including the fin, may be of the desired material, such as aluminum. The body portion of the shuttle is preferably positioned to run on the usual shuttle race of the loom with the fin projecting towards the fell of the cloth and into the air gap between the core sections. While the shuttle boxes and the apparatus of this invention are herein shown as mounted upon the lay, it is of course not necessary that they should move with the lay, but instead they may be mounted upon a separate mechanism or in fixed position on the loom frame with the lay acting simply to beat in the filling. It will be noted that the construction of the shuttle as above described lends itself readily to operation in the ordinary type of loom. The fin being relatively thin may project

well forward of the shuttle body into the shed without danger of engagement with and damage to the warps.

The checking of the shuttle may be accomplished by the usual mechanical or other means, but it is herein shown as accomplished by one feature of the present invention. For that purpose the same electrical apparatus used to pick the shuttle is employed. In this case the coils of the core section of the stator are connected with the source of direct current as the translator of the shuttle enters the air gap in the core sections. Consequently as the fin or effective translator passes between the core sections, its velocity is checked by the damping action caused by the fin cutting the flux set up by the coils. In thus cutting the flux a current is set up in the fin which coacts with the flux to gradually bring the shuttle to rest.

The traveling magnetic field is produced by a polyphase alternating current, preferably the usual three-phase current, and the magnetic field for checking the shuttle may be produced by a direct current. Suitable means are provided for controlling the timing of the operations of the apparatus, or in this case the timing of the picking and checking of the shuttle, and for that purpose there are herein shown a plurality of cams mounted upon a rotating shaft driven at the proper speed and properly adjusted on the shaft to close and open switches at properly timed intervals with these switches placed in the electric circuits leading to the core sections of the stators.

Referring now to the construction shown in Figs. 1 to 6, inclusive, there is shown a loom in which the lay 1 with the exception of the shuttle boxes may be of standard construction having the swords 2 and 3 which are provided with the upright portions 4 and 5 to which the hand rail 6 is secured. The reed 7 is secured at its lower edge in a recess in the lay and at its upper edge in a recess in the hand rail. The lay is extended at both ends beyond the reed as is the usual practice, but in place of the conventional mechanical pick motion, the ends of the lay are shown as supporting an electro-dynamic apparatus of this invention designated generally at 8 and 9. The apparatus at each end is similar in construction and electrically designed to move the shuttle in opposite directions toward the center of the lay. The core sections and coils of the apparatus may be arranged in any desired manner. A preferred construction consists of upper and lower laminated core sections 10 and 11, the lower core section being provided with transverse slots 12 to receive the coils 13. The core sections are of a length determined by the practical limits of size and weight of the parts and the required velocity of the shuttle.

The core sections are supported one above the other by any suitable means to form a narrow air gap 14. As herein shown they are supported by means of a metal frame 15. The upper core section is secured to the frame by means of angle brackets 16 which may be integral with, riveted to, or fastened in any desirable manner to the frame 15, the downwardly depending portions of the angle brackets being secured to the core section by means of suitable rivets or bolts 17. The lower core section is similarly secured to the frame 15 by means of angle brackets 18, the upward projecting portions being secured to the core section by means of bolts or rivets 19.

In order more effectively to support the upper core section, the frame 15 is extended rearward

- of the loom above the shuttle box. This extension is in the form of two or more girders 20 extending to and downward along the rear wall of the lay to which they are secured. The angle brackets 16 5 at the rear wall of the core section 10 are secured to the girders 20 by means of bolts or rivets 21. The bolts or rivets 17 and 19 pass through those portions of the brackets 16 and 18 which lie along the side walls of the core sections by 10 to add rigidity to the laminated core sections by clamping the laminations firmly between the angle brackets. But any suitable means may be employed to support the core sections.

The frame 15 is secured to the lay in any suitable way as by means of the bolts 22 passing therethrough and through ears 23 depending from the frame 15. The core sections desirably are so positioned with respect to the raceway that the rear face of the upper core section 10 15 constitutes the front wall of the shuttle box, and may be faced with fibre or leather as shown at 24. The rear wall of the shuttle box is formed with a shuttle guiding member 25 secured to the upper face of the lay. The travel of the shuttle 20 is shown as limited by an adjustable stop 26 secured at the end of the lay and desirably faced with shock absorbing material such as fibre or leather to avoid any tendency of the shuttle to rebound. The core sections are mounted vertically 25 on the lay in such position that the upper face of the lower core section is flush with the plane of the raceway 27 of the lay.

- The projecting portions 28 of the coils 13 extend from the rear face of the core section 11 into 30 a recess 29 formed in the lay. The recess 29 is covered by a plate 30 secured in the lay upon which the shuttle rests when in the shuttle box. The frame 15 is formed to pass around the forwardly projecting portions 31 of the coils. The 35 shuttle-guiding member 25 is faced desirably with leather or other suitable material as shown at 33, and is positioned to engage the rear wall of the shuttle when the shuttle is in the shuttle box, its forward face being flush with the face of the reed. 40
- 45 The body portion of the shuttle may be constructed of any suitable material such as wood while the fin 34 projecting from the front face must be of electrically-conductive material and for efficiency must have a low electrical resistance. 50 A preferred form of shuttle from the viewpoint of both electrical and mechanical efficiency is a shuttle constructed entirely of the required material for the fin such as aluminum.

- In the operation of the apparatus, currents of 55 high amperage are induced within the fin in the form of eddy currents. In order for the apparatus to function efficiently, a low resistance path must be provided beyond the core sections to establish a closed circuit for these eddy currents. 60 To provide for this the fin is extended forward an appreciable amount beyond the air gap. If the body of the shuttle is not of electrically-conductive material, the extension of the fin by which it is secured to the body of the shuttle must project an appreciable amount rearward of the air gap to provide a path for the eddy currents.

- As already pointed out, only those features of a standard form of loom with which a preferred and illustrated embodiment of the invention is 70 shown are disclosed herein. The mechanisms for actuating the harnesses, the take-up and let-off and all the various adjunctive mechanisms of a loom are not here involved and may be of any desired type. In the construction illustrated, the 75 swords 2 and 3 of the lay 1 are mounted on the

usual lay rocker shaft 35 journalled in the loom sides 36 and the lay is actuated from the crank shaft 37 by the pitmen 38. The shed is formed by suitable shed forming mechanism including harness frames 39. As the cloth is woven, the 5 warps are drawn from the usual warp beam 40, the finished cloth passes over the breast beam 41 and is wound up on the cloth roll 42.

The electrical connections to the shuttle picking and checking apparatus at the ends of the 10 lay are made through three-wire cables 43 which are shown as extended down along the swords 2 and 3, and connected to an outlet box 44 upon each loom side by means of short sections of flexible cable 45. Cables 46 leading from the outlet 15 box 44 are connected to the contact arms 47 of a switching mechanism indicated generally at 48, and mounted upon a bracket 49 extending inward from the loom side 36. Situated upon the bracket 49 in position to be engaged by the contact arms 20 47 of the switches, are a series of contact plates 50 which are in turn connected to the source of current employed to operate the apparatus, certain of the contact plates being connected to a three-phase, three-wire electric source, while the 25 remaining contact plates are connected to a direct current electric source.

The contact arms 47 are engaged by a series of cams 51, 52, 53 and 54 mounted upon a shaft 55 journalled in the loom sides 36 and driven from 30 the crank shaft 37 by means of a gear 56 upon the shaft 55 meshing with a gear 57 on the crank shaft. To produce the proper timed relation for actuation of the switches the gears 56 and 57 have a 2 to 1 ratio. 35

In order to insure that the shuttle shall properly enter the shuttle box if accidentally deflected from its normal path, the inner corner 58 at the inner end of the upper core section 10 is slightly curved. The curved surface thus formed 40 acts to guide the shuttle accurately into the shuttle box. The lower corner of the inner end of the core section 10 also is slightly curved as shown at 59. The curved surface thus formed acts to guide the shuttle by its fin into its proper 45 horizontal plane should it have a tendency to rise from the shuttle race. A horn 60 is provided for each shuttle box and is situated above the path of the body of the shuttle and is secured preferably to the uprights 4 and 5 of the lay swords 50 2 and 3. The horns 60 serve to guide the body of the shuttle into its proper position within the shuttle box. These horns are shown broken away and may extend as far over the shuttle box to the end of the lay as is desirable. 55

The electrical design of the electro-dynamic apparatus must be such that a traveling magnetic field is produced within the core sections when the coils are connected to the polyphase alternating electric current, and the number and 60 size of the turns in the coils must be sufficient to create the desired velocity of the shuttle. The actual design adopted to attain the desired result is immaterial. A desirable form is illustrated in the drawings wherein the coils 13 are 65 set in slots 12. When the coils are energized, a magnetic field is created in the core section 11. The lines of force or flux of the field traverses the air gap 14 and enters the core section 10 where it travels longitudinally and returns to the 70 core section 11 at a point where the flux is of opposite polarity as shown diagrammatically in Fig. 6.

The coils may be arranged in any suitable manner to produce a traveling field. They are 75

so arranged as desirably to produce a field which moves smoothly and with sufficient speed properly to accelerate the shuttle. It has been determined that a polyphase alternating current produces a satisfactory field. It is possible, however, to create a traveling field by employing direct current used in connection with a mechanical commutating means which would supply successively each coil of the winding with direct current of proper polarity. In connection with the use of polyphase current it is within the scope of the invention to employ a current of any suitable frequency.

The particular design illustrated employs three-phase alternating current which is connected to the coils in the conventional Y circuit. The delta connection may be used however. There are shown herein two groups of coils, one group occupying the slots of one-half of the core section 11 at one end thereof, while the other group occupies the remaining slots. Each group contains a set of coils for each phase of the circuit, or three sets of coils in each group. Because the succession of slots terminates at the two ends of the core, it is desirable to use some such unusual arrangement of coils as that shown, in order to make use of all the slots, produce a good flux distribution along the core, and fulfill other requirements of efficiency.

The arrangement of coils is shown in Figs. 4 and 5. The first turn of the coil set 61 is connected to the wire 62 carrying the first phase of the circuit. The first turn of the coil set 63 is connected to the wire 64 carrying the third phase, the coils 63 being wound in a reverse direction to that of the coils 61, thereby producing a reversed field. The first turn of the coil set 65 is connected to the wire 66 which carries the second phase of the circuit. The other ends of the coils 61, 63 and 65 are connected, respectively, to the first turn of the coils 67, 68 and 69 in the second group, while the other ends of these coils are connected to the neutral point 10. The coils 68 are connected in a reverse direction in the same manner as the coils 63. The phases are, therefore, as well balanced as is possible.

The velocity required of the shuttle varies with different types of looms, but the velocity of the field produced by a 60-cycle current with proper coil spacing is adequate to produce the highest reasonable speed of travel for the shuttle.

The preferred design of the coil system is shown in Fig. 5. Each coil is divided in two sections which are connected in series, each coil section occupying different slots in the core section. By thus dividing the coils a better distribution of flux throughout the core section is obtained, but the coils may be divided into any desired number of sections. The apparatus at both ends of the lay is similar with the exception that the groups of coils are connected to the three-phase source in the proper order to propel the shuttle in opposite directions or toward the center of the lay.

The operation of the described apparatus is as follows:—Assuming the shuttle to be at rest within the left-hand shuttle box, the cam 54 upon the shaft 55 first engages the three-contact arms 11 of the switch mechanism 48, the arms 11 being connected to the left-hand apparatus, and the arms 11 are forced into contact with the contact plates 12 which are connected to the three-phase source of current 13. The left-hand apparatus is thereby energized and acts to eject the shuttle therefrom. The shuttle passes through

the shed and enters the right-hand shuttle box. The cam 54 then permits the contact arms 11 to spring into their open circuit position. At the instant the shuttle enters the right-hand box, the cam 53 causes the contact arms 14 to engage the contact plates 15 which are connected to the direct current source 16. The contact arms 14 are connected by means of the wires 17 to two phases of the right-hand apparatus. The stationary field thus set up therein acts upon the fin of the shuttle to retard the velocity thereof, and bring it gradually to rest within the shuttle box according to the natural law applying to such a combination of elements. The intensity of this field should be sufficient to retard the flight of the shuttle to such an extent that it has a very slight movement when it reaches the stop 26.

When the shuttle has come to rest within the right-hand box, the cam 53 permits the contact arms 14 to spring into open circuit position. After the interval of time required for the beating in of the filling, the cam 52 acts to cause the contact arms 18 to engage the contact plates 19 which are connected to the three-phase source 13. The contact arms 18 are connected to the right-hand apparatus which acts to eject the shuttle therefrom, and causes it to enter the left-hand shuttle box. The cam 52 then permits the contact arms 18 to spring into open circuit position, and as the shuttle enters the left-hand box, the cam 51 acts to force the contact arms 20 into engagement with the plates 21 which are connected to the direct current source 16. The arms 20 are connected to two phases of the coils upon the left-hand apparatus by means of the wires 22. The shuttle thereby is checked in the left-hand shuttle box in the same manner that it was checked in the right-hand shuttle box. The above sequence of operations is repeated to form a continuous weaving process.

In order accurately to regulate the velocity of the shuttle, a rheostat 83 is inserted in the three-phase line 13. The rheostat includes resistances for each of the phases of the circuit with contact arms, one for each resistance, which are movable in unison to adjust the resistance of the circuit the required amount to produce the correct velocity of the shuttle. Likewise the checking of the shuttle may be accurately adjusted by means of the rheostat 84 inserted in the direct current line 16. Other means than the rheostats 83 and 84 may be employed to vary the force exerted upon the translator. Any suitable means may be used for this purpose which is capable of modifying the impulse exerted upon the translator. It is not necessary to describe the operation of the remaining elements of the loom since they are or may be of usual construction and function in a manner well known to those skilled in the art.

There are many methods of applying the principles of the invention to propelling a shuttle. Some further practical methods will be outlined herein. As already pointed out, Fig. 6 illustrates diagrammatically at one point of its travel the path of the magnetic field resulting from the arrangement of the elements above described in detail. As the design of the parts digresses from the fin type of shuttle, as shown in Fig. 6, the problem arises of designing a shuttle having the proper electrical and magnetic properties as well as sufficient space for a bobbin or other filling carrier. In addition to these qualifications, the shuttle also must be as light as possible.

Fig. 7 illustrates one variation in which there are two electro-magnetic members having core 75

sections 85 and 86 between which a shuttle moves. The body portion of the shuttle may be constructed of aluminum or other electrically-conducting material. Such a construction, while operable, would be inefficient since the air gap between the two electromagnetic members of necessity would be relatively great. The high reluctance imposed by this gap would necessitate coils having a large number of ampere turns to produce the necessary flux density across the gap. In order to reduce the reluctance, a section of iron 87 is secured to the bottom face of the shuttle. A plurality of electrical conductors 88 are embedded transversely in the section 87 and are 15 welded or otherwise bonded at their ends to conducting plates 89 and 90 which provide the necessary electrical path for the current induced in the conductors. The section of iron 87 preferably extends substantially the length of the shuttle. In this type of apparatus, the axes of the coils 91 are horizontal and the axis of the path of the flux represented by the broken line 92 is at right angles thereto.

Fig. 8 shows a preferred design to be used in 25 a double fabric loom for simultaneously actuating two shuttles. The core sections are of substantially the same length as in the other forms of the device. The shuttles are arranged one above the other, the lower shuttle 99 bearing 30 upon the upper face of an electro-magnetic member 100, while the upper shuttle 101 bears upon an intermediate core section 102. Each shuttle is provided with iron sections 103 secured to its sides to form a path for the flux. 35 The sections 103 have embedded therein a plurality of electric conductors 104 disposed transversely of the sections 103 and welded or otherwise bonded at their ends to conducting plates 105. Situated close to the upper edge of the sections 103 of the shuttle 101 are two electro-magnetic members 106 and 107. When the electro-magnetic members are energized the flux in the coils of the member 106 will circulate about a generally horizontal axis, and at its pole tip will 40 be conducted downwardly along the side of the upper shuttle through the iron section 103 through the intermediate core 102, into the iron section 103 in the lower shuttle and thence into the member 100 wherein it travels longitudinally 45 and returns upwardly with the flux of opposite polarity through the same iron sections 103 to the core section of the member 106. The flux created by the member 107 passes downwardly through the iron sections 103 at the opposite 50 sides of the shuttle into the member 100, and upwardly into the core section of the member 107 in a manner similar to the flux circulation to the member 106. The coils on the electro-magnetic member 100 are wound and connected 55 in the circuit in a manner to aid and build up the intensity of the flux in the system.

In these cases the core sections of the magnetic element of the apparatus are extended longitudinally, as shown in Fig. 1, well beyond the portion carrying the exciting coils. This extended portion acts to minimize the distortion of the paths of the magnetic flux generated by the end coils, thereby preventing an abnormal condition of the field with its consequent effect on 65 the velocity of the shuttle at the ends of the magnetic element. Thus a substantially uniform density of the magnetic field is provided throughout its path of travel.

While the translator, in the forms of the invention illustrated, is shown as itself carrying

the filling, it will, of course, be understood that the filling carrier need not be a physical part of the translator and, while there would be certain differences in the operation of the apparatus under these circumstances, the broad principles of the invention in its application to a loom would still be applicable.

In the embodiments of the invention thus far illustrated, the traveling magnetic field has been shown as moving in a rectilinear path with the core sections correspondingly rectilinear. But in its broader aspects, the invention includes an apparatus in which the field travels in a defined 15 terminated path. As illustrating somewhat the application of the scope of the invention as specifically applied to a loom or similar mechanism, reference may be made to the diagrammatic illustration of Fig. 9.

In Fig. 9 a filling carrier 108 having an electrically-conductive fin 109, which may be of the general type already disclosed, is shown secured to the end of a radius arm 110 pivoted at 111 so that the path of the translator is confined to the arc of a circle. The electromagnetic elements are shown as of the general type illustrated in Fig. 1 but with the core sections 112 disposed on a circular arc in the path of travel of the fin 109 and spaced apart to define the limits of the path through which the translator travels.

In Fig. 13 there is shown an application of the invention for causing the reciprocatory travel of a translator comprising a filling carrier 113 having an electrically conductive fin 114 along a defined terminated path. This fin extends between the core sections 115, the lower of which is shown as carrying the exciting coils and the upper of which above the fin is shown as a return core section, thus causing a return path for the magnetic flux. The core sections 115 extend throughout and between the limits of the path of travel of the translator and are shaped to conform to this path and the exciting coils are actuated to initiate, accelerate, and decelerate the movement of the translator, all according to 45 the principles hereinbefore set forth, but in this case the translator is nowhere projected into space.

A further practical method of reciprocating the shuttle or a translator of any character which is within the scope of the invention but has not been specifically set forth in the foregoing description is as follows. A pair of electrodynamic units may be supplied with an uninterrupted flow of alternating current and so disposed relatively to each other as to create oppositely acting impulses upon the translator. The translator when placed within one of the units and the power turned on, would be projected therefrom and at the end of its flight 60 would enter the other unit. Since the impulse in the second unit is acting in opposition to the entering movement of the translator, such impulse would act to decelerate the movement of the translator, and when its velocity was reduced to zero within the unit, the impulse would immediately accelerate the translator and project it from the unit causing it to travel in the opposite direction and again to enter the first unit. Upon entering this unit the translator 70 would again be decelerated and projected therefrom. This process could be maintained automatically, the period of reciprocation being determined by the power supplied to the translator, its inertia, the distance traveled, and the fric- 75

tional resistance opposing its motion, if a slightly decreased power be supplied to the units when they act to decelerate the translator thereby to compensate for the friction encountered in traveling from one unit to the other.

This decrease of power can be obtained, for instance, by the direct mechanical action of the movement of the translator in its path upon a mechanical switching device interposed in the electrical circuit.

An example of such an apparatus is diagrammatically illustrated in Fig. 12 as applicable to the picking mechanism of a loom. There are illustrated two electro-dynamic units 116 and 117 which may represent the electrodynamic picking devices at opposite ends of the lay with a translator in the form of a filling carrier or shuttle 118 having the thin fin 119. The supply 120 of three-phase alternating current has interposed in its passage to each of the electrodynamic units at each end of the lay mechanical switching devices indicated respectively at 121 and 122, each of which operates by the direct mechanical action of the movement of the translator to effect the desired decrease of power supplied to the electrodynamic unit when it acts to decelerate the translator and to effect the restoration of the power supply to the electrodynamic unit when it acts to accelerate the translator.

As previously explained, the deceleration or checking movement of the translator may be effected either by direct current, single phase current or multiphase current and an apparatus for effecting such deceleration by a three-phase current is illustrated in Fig. 10. Therein the electrodynamic units are indicated at 123 and 124 alternately supplied with a three-phase current 125 through a device 126 for altering the connections from the main three-phase supply to each electrodynamic unit as required to cause the magnetic field to travel in the direction required either for acceleration or deceleration of the translator. A further apparatus for effecting such deceleration by a single phase current is illustrated in Fig. 11. Therein the electrodynamic units are indicated at 127 and 128. In this case the three-phase alternating current 129 is connected to the device 130 which in turn is connected to the electrodynamic units and which acts to alter the connections from the main three-phase supply 129 to each electrodynamic unit so as to cause the magnetic field to travel when required in each unit in the direction required for acceleration of the translator and so as to cause when required a single phase magnetic field in each electrodynamic unit to be set up to decelerate the translator.

Having thus described the invention, what is claimed as new, and desired to be secured by Letters Patent, is:

1. An electro-dynamic apparatus for initiating and accelerating and for decelerating the movement of a body in a rectilinear path comprising an electro-magnetic system having a core of rectilinear form presenting a coil carrying section and a return section separated by a narrow air gap, exciting coils on the coil carrying section, and a translator having a thin electrically conductive non-magnetic fin fitting the air gap, means for connecting a polyphase alternating current to the said coils to cause the said system to produce a flux of variable density whose point of maximum density travels longitudinally of the core and which flux acts,

when the fin is within its field, to induce current therein and co-acts with the magnetic field of such current to initiate and accelerate the movement of the translator longitudinally of the core in the direction of said travel and also 5 co-acts with the magnetic field of such current to decelerate the movement of the translator longitudinally of the core when the fin is moved within the field in the opposite direction.

2. An electro-dynamic apparatus for initiating 10 and accelerating and for decelerating the movement of a body in a rectilinear path comprising an electro-magnetic system having a core of rectilinear form and exciting coils, and an electrically conductive body, means for connecting a 15 polyphase alternating current to the said coils to cause the said system to produce a flux of variable density whose point of maximum density travels longitudinally of the core and which flux acts, when the body is within its field, to induce 20 current therein and co-acts with such current to initiate and accelerate the movement of the body longitudinally of the core in the direction of said travel, and means for connecting a direct current to said coils to cause the said system to produce 25 a stationary flux which flux acts, when the body is moved within its field, to induce current therein and co-acts with such current to decelerate the movement of the body.

3. An electro-dynamic apparatus for initiating 30 and accelerating and for decelerating the movement of a body in a rectilinear path comprising an electro-magnetic system having a core of rectilinear form and exciting coils, and an electrical- 35 conductive body, means for connecting a poly- phase alternating current to the said coils to cause the said system to produce a flux of variable density whose point of maximum density travels longitudinally of the core and which flux acts, when the body is within its field, to induce 40 current therein and co-acts with such current to initiate and accelerate the movement of the body longitudinally of the core in the direction of said travel and means for connecting a single phase alternating current to said coils to cause the said 45 system to produce a stationary oscillating flux, which flux acts, when the body is moved within its field, to induce current therein and co-acts with such current to decelerate the movement of the body.

4. An electro-dynamic apparatus for initiating 50 and accelerating the movement of a body in a rectilinear path comprising an electro-magnetic system having a core of rectilinear form, pre- 55 senting a coil carrying section and a return sec- tion separated by an air gap, an electrically conductive body fitting the air gap, and means for energizing the said coils to produce a flux of variable density whose point of maximum density travels longitudinally of the core in one di- 60 rection only and which flux acts, when the body is within its field, to induce current therein and co-acts with such current to cause the body to be projected from the field in the said direction.

5. An electro-dynamic apparatus for initiating 65 and accelerating the movement of a body in a rectilinear path comprising an electro-magnetic system having a core of rectilinear form, pre- 70 senting a coil carrying section and a return sec- tion separated by an air gap, a non-magnetic electrically conductive body fitting the air gap, and means for energizing the said coils to pro- 75 duce a flux of variable density whose point of maximum density travels longitudinally of the core in one direction only and which flux acts,

when the body is within its field, to induce current therein and co-acts with such current to cause the body to be projected from the field in the said direction.

- 5 6. An electro-dynamic apparatus for initiating and accelerating the movement of a body in a rectilinear path comprising an electro-magnetic system having a core of rectilinear form, presenting a coil carrying section and a return section separated by an air gap, a composite body of magnetic elements and of non-magnetic electrically conductive elements fitting the air gap, and means for energizing the said coils to produce a flux of variable density whose point of maximum density travels longitudinally of the core in one direction only and which flux acts, when the body is within its field, to induce current therein and co-acts with such current to cause the body to be projected from the field in the said direction.
- 10 7. An electro-dynamic apparatus for initiating and accelerating the movement of a body in a defined terminated path comprising an electro-magnetic system having a core presenting a coil carrying section and a return section extending along at opposite sides of and conforming to said path, an electrically conductive body, and means for energizing the said coils to produce a flux of variable density whose point of maximum density travels longitudinally of the core and in conformity to said path in one direction only and which flux acts, when the body is within its field, to induce current therein and co-acts with such current to cause the body to be projected from the field in the said direction at the maximum speed attained by the body.
- 15 8. An electro-dynamic apparatus for initiating and accelerating the movement of a body in a rectilinear path comprising a core having two parallel sections of rectilinear form with an air gap between the sections, an electrically conductive body fitting the air gap and extending well beyond the air gap at each side to provide free paths for the induced currents therein, an electro-magnetic means upon one of the core sections, and means for energizing the said electro-magnetic means to produce a flux of variable density whose point of maximum density travels longitudinally of the core and which flux acts, when the body is placed within the air gap, to induce current therein and co-acts with such current to move the body longitudinally within the air gap and project it therefrom.
- 20 9. An electro-dynamic apparatus for initiating and accelerating the movement of a body in a rectilinear path comprising a core having two parallel sections of rectilinear form with a narrow air gap between the sections, a thin non-magnetic electrically conductive body fitting the air gap and extending well beyond the air gap at each side to provide free paths for the induced currents therein, an electro-magnetic means upon one of the core sections, and means for energizing the said electro-magnetic means to produce a flux of variable density whose point of maximum density travels longitudinally of the core and which flux acts, when the body is placed within the air gap, to induce current therein and co-acts with such current to move the body longitudinally within the air gap and project it therefrom.
- 25 10. An electro-dynamic apparatus for initiating and accelerating the movement of a body in a rectilinear path comprising a core having two parallel sections of rectilinear form with a narrow air gap between the sections, a thin composite body of magnetic elements and of non-magnetic

electrically conductive elements fitting the air gap and extending well beyond the air gap at each side to provide free paths for the induced currents therein, an electro-magnetic means upon one of the core sections, and means for energizing the said electro-magnetic means to produce a flux of variable density whose point of maximum density travels longitudinally of the core and which flux acts, when the body is placed within the air gap, to induce current therein and co-acts with such current to move the body longitudinally within the air gap and project it therefrom.

11. An electro-dynamic apparatus for initiating and accelerating and for decelerating the movement of a body in a rectilinear path comprising a core having two parallel sections of rectilinear form with an air gap between the sections, exciting coils on the core, an electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with such current to initiate and accelerate the movement of the body longitudinally within the air gap in the direction of said travel and to project it from the air gap, and also co-acts with such current to decelerate the movement of the body when the body is moved within the air gap in the opposite direction.

12. An electro-dynamic apparatus for initiating and accelerating and for decelerating the movement of a body in a rectilinear path comprising a core having two parallel sections of rectilinear form with an air gap between the sections, exciting coils on the core, an electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with such current to initiate and accelerate the movement of the body longitudinally within the air gap in the direction of said travel and to project it from the air gap, and means for connecting a direct current to said coils to cause the said system to produce a stationary flux, which flux acts, when the body is moved within the air gap, to induce current therein and co-acts with such current to decelerate the movement of the body.

13. An electro-dynamic apparatus for initiating and accelerating and for decelerating the movement of a body in a rectilinear path comprising a core having two parallel sections of rectilinear form with an air gap between the sections, exciting coils on the core, an electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with such current to initiate and accelerate the movement of the body longitudinally within the air gap in the direction of said travel and to project it from the air gap, and means for connecting a single phase alternating current to said coils to cause the said system to produce a stationary oscillating flux, which flux acts, when the body

is moved within the air gap, to induce current therein and co-acts with such current to decelerate the movement of the body.

magnetic electrically-conductive material fitting the air gap and extending at both sides thereof to provide return paths for eddy currents, and having sections of magnetic material extending transversely thereof to form flux paths between the core sections, the said apparatus acting when a polyphase alternating current is connected to the winding to produce a magnetic flux traveling longitudinally of the core from one end to the other and which flux acts to induce current in the translator and co-acts with such current to move the translator therewith.

14. An electro-dynamic apparatus for initiating and accelerating and for decelerating the movement of a body in a rectilinear path comprising a core having two parallel sections of rectilinear form with a narrow air gap between the sections, exciting coils on the core, a thin non-magnetic electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with the magnetic field of such current to initiate and accelerate the movement of the body longitudinally within the air gap in the direction of said travel and to project it from the air gap, and also co-acts with the magnetic field of such current to decelerate the movement of the body when the body is moved within the air gap in the opposite direction.

15. An electro-dynamic apparatus for initiating and accelerating and for decelerating the movement of a body in a rectilinear path comprising a core having two parallel sections of rectilinear form with a narrow air gap between the sections, exciting coils on the core, a thin non-magnetic electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with such current to initiate and accelerate the movement of the body longitudinally within the air gap in the direction of said travel and to project it from the air gap, and means for connecting a direct current to said coils to cause the said system to produce a stationary flux, which flux acts, when the body is moved within the air gap, to induce current therein and co-acts with such current to decelerate the movement of the body.

16. An electro-dynamic apparatus for initiating and accelerating and for decelerating the movement of a body in a rectilinear path comprising a core having two parallel sections of rectilinear form with a narrow air gap between the sections, exciting coils on the core, a thin non-magnetic electrically conductive body fitting the air gap, means for connecting a polyphase alternating current to the coils to produce a flux of variable density whose point of maximum density travels longitudinally of the core sections and which flux acts, when the body is within the air gap, to induce current therein and co-acts with such current to initiate and accelerate the movement of the body longitudinally within the air gap in the direction of said travel and to project it from the air gap, and means for connecting a single phase alternating current to said coils to cause the said system to produce a stationary oscillating flux, which flux acts, when the body is moved within the air gap, to induce current therein and co-acts with such current to decelerate the movement of the body.

17. An electro-dynamic apparatus comprising a stator and a translator, the said stator comprising a pair of terminated core sections equispaced by an air gap and a polyphase coil winding on the core, the translator comprising a fin of non-

magnetic electrically-conductive material fitting the air gap and extending at both sides thereof to provide return paths for eddy currents, and having sections of magnetic material extending transversely thereof to form flux paths between the core sections, the said apparatus acting when a polyphase alternating current is connected to the winding to produce a magnetic flux traveling longitudinally of the core from one end to the other and which flux acts to induce current in the translator and co-acts with such current to move the translator therewith.

18. An electro-dynamic apparatus comprising a stator and a translator, the said stator comprising a pair of terminated core sections equispaced by a narrow air gap and a polyphase coil winding on the core, the translator comprising a thin fin of electrically-conductive material fitting the air gap and extending at both sides thereof to provide return paths for eddy currents, the said apparatus acting when a polyphase alternating current is connected to the winding to produce a magnetic flux traveling longitudinally of the core from one end to the other and which flux acts to induce current in the translator and co-acts with such current to move the translator therewith.

19. An electro-dynamic apparatus for initiating and accelerating and for decelerating the movement of a body in a rectilinear path comprising an electro-magnetic system having a core of rectilinear form and exciting coils on said core, an electrically conductive body, means for energizing some of said coils to produce a flux of variable density whose point of maximum density travels longitudinally of the core, and means for energizing other of said coils to produce a stationary flux, the former flux acting, when the body is within its field, to induce current therein and co-acting with said current to initiate and accelerate the movement of the body longitudinally of the core in the direction of the flux travel, and the latter flux acting when the body is moved in its field to induce current therein and co-acting with such current to decelerate the movement of the body.

20. An electro-dynamic apparatus for accelerating and for decelerating the movement of a body in a rectilinear path comprising an electro-magnetic system having a core of rectilinear form and exciting coils on said core, an electrically conductive body, means for energizing some of said coils to produce a flux of variable density whose point of maximum density travels longitudinally of the core, and means for energizing other of said coils to produce a stationary flux, the said fluxes acting electro-dynamically respectively to accelerate and to decelerate the movement of the body longitudinally of the core.

21. A loom having mounted thereon at the side of the shed an electro-dynamic apparatus comprising a pair of parallel rectilinear core sections extending transversely of the loom and separated by an air gap, a polyphase coil winding on said core producing when connected with a corresponding polyphase alternating current a magnetic field traveling longitudinally toward the center of the loom and across the air gap, and a cooperating filling carrier presenting an electrically conductive translator extending through and beyond both sides of the air gap and acted upon electro-dynamically to be accelerated by the field and projected therefrom across the loom.

22. A loom having mounted thereon in alignment at each side of the shed an electro-dynamic

- apparatus comprising a pair of parallel rectilinear core sections extending transversely of the loom and separated by an air gap, a polyphase coil winding on said core, means for alternately connecting a corresponding polyphase alternating current and a direct current to said coil winding, and a cooperating filling carrier presenting an electrically conductive translator extending through and beyond both sides of the air gap, 5 each said apparatus acting when connected to the alternating current to produce a magnetic field traveling longitudinally toward the center of the loom and across the air gap acting to induce current within the translator and co-acting therewith to project the filling carrier across the loom and each said apparatus when connected to the direct current acting to induce current within the translator and co-acting therewith when the translator is projected into its field to bring the 10 filling carrier to rest.
23. A loom provided at each side with an electro-dynamic means alternately energized by a polyphase, alternating electric current and by a direct current and acting to induce current within an electrically conductive filling carrier and co-acting therewith to project the filling carrier from said means and across the loom when energized by the alternating current and to bring to rest the filling carrier projected from the opposite side of the 15 loom when energized by the direct current.
24. A loom provided at each side with an electro-dynamic means alternately energized by a polyphase, alternating electric current and by a single phase alternating current and acting to induce current within an electrically conductive filling carrier and co-acting therewith to project the filling carrier from said means and across the loom when energized by the polyphase alternating current and to bring to rest the filling carrier projected from the opposite side of the loom when energized by the single phase alternating current.
25. A loom comprising a lay, means for swinging the lay forward and rearward, the said lay having mounted thereon at each end an electro-dynamic apparatus comprising a pair of parallel rectilinear core sections extending longitudinally of the lay and separated by an air gap, a polyphase coil winding on each pair of core sections producing when connected with a corresponding polyphase alternating current a magnetic field traveling longitudinally toward the center of the loom and across the air gap, and a cooperating filling carrier presenting an electrically conductive translator extending through and beyond both sides of the air gap and acted upon electro-dynamically to be accelerated by the field of each apparatus and projected therefrom to the opposite end of the lay.
26. A loom comprising a lay, means for swinging the lay forward and rearward, the said lay having mounted thereon at each end and in alignment an electro-dynamic apparatus comprising a pair of parallel rectilinear core sections extending longitudinally of the lay and separated by an air gap, a polyphase coil winding on each pair of core sections, means for alternately connecting a corresponding polyphase alternating current and a direct current to each of said coil windings, and a cooperating filling carrier presenting an electrically-conductive translator extending through and beyond both sides of the air gap when located therein, each said apparatus 70 acting when connected to the alternating current to produce a magnetic field traveling longitudinally toward the center of the loom and across the air gap acting electro-dynamically upon the translator to project the filling carrier across the loom and each said apparatus when connected to the direct current acting electro-dynamically upon the translator projected into its field to bring the filling carrier to rest.
27. A loom comprising a lay, means for swinging the lay forward and rearward, the said lay having mounted thereon at each end an electro-dynamic means alternately energized by a polyphase alternating current and by a direct current, and each acting electro-dynamically upon an electrically conductive filling carrier alternately to project the filling carrier from said means and across the loom when energized by the alternating current and to bring to rest the filling carrier projected from the opposite side of the loom when energized by the direct current.
28. A loom having the construction defined in claim 22, in which the means for alternately connecting the alternating current and the direct current to said coil winding comprises a series of switches and means for operating the switches in timed relation to the operation of the loom.
29. A loom comprising the construction defined in claim 23, together with a series of switches and means for operating the switches in timed relation to the operation of the loom to connect the alternating current and the direct current for alternately energizing the said electro-dynamic means.
30. A loom comprising the construction defined in claim 24, together with a series of switches and means for operating the switches in timed relation to the operation of the loom to connect the polyphase alternating current and the single phase alternating current for alternately energizing the said electro-dynamic means.
31. A loom having the construction defined in claim 26, in which the means for alternately connecting the alternating current and the direct current to said coil winding comprises a series of switches and means for operating the switches in timed relation to the operation of the loom.
32. A loom having the construction defined in claim 27, together with a series of switches and means for operating the switches in timed relation to the operation of the loom to connect the alternating current and the direct current for alternately energizing the said electro-dynamic means.
33. A loom shuttle comprising a body portion and a thin fin of non-magnetic electrically conductive material projecting longitudinally of the body and laterally therefrom and capable when an electric current is induced therein to effect longitudinal propulsion of the shuttle through the coaction of said induced current with a traveling magnetic field.
34. A loom shuttle comprising a body portion and a thin fin of electrically conductive material projecting longitudinally of the body and laterally therefrom and capable when an electric current is induced therein to effect longitudinal propulsion of the shuttle through the coaction of said induced current with a traveling magnetic field.
35. A loom shuttle comprising a body portion and a thin fin of magnetic elements and of non-magnetic electrically conductive elements projecting longitudinally of the body and laterally therefrom and capable when an electric current is induced therein to effect longitudinal propulsion of the shuttle through the coaction of said induced current with a traveling magnetic field.

36. A filling carrier comprising a body portion and a thin fin of non-magnetic electrically conductive material projecting longitudinally of the body and laterally therefrom and capable when an electric current is induced therein to effect longitudinal propulsion of the filling carrier through the coaction of said induced current with a traveling magnetic field.

37. A filling carrier comprising a body portion and a thin fin of electrically conductive material projecting longitudinally of the body and laterally therefrom and capable when an electric current is induced therein to effect longitudinal propulsion of the filling carrier through the coaction of said induced current with a traveling magnetic field.

38. A filling carrier comprising a body portion and a thin fin of magnetic elements and of non-magnetic electrically conductive elements projecting longitudinally of the body and laterally therefrom and capable when an electric current is induced therein to effect longitudinal propulsion of the filling carrier through the coaction of said induced current with a traveling magnetic field.

39. A filling carrier for a loom having a thin fin of non-magnetic electrically conductive material projecting longitudinally thereof and laterally therefrom and inserts of material of high magnetic permeability extending transversely from face to face of the fin the said fin capable when an electric current is induced in the non-magnetic electrically conductive material thereof of effecting longitudinal propulsion of the filling carrier through the coaction of said induced current with a traveling magnetic field.

40. A loom shuttle comprising a body portion and a thin fin of non-magnetic electrically conductive material projecting longitudinally of the body and laterally therefrom and inserts of material of high magnetic permeability extending transversely from face to face of the fin the said fin being capable when an electric current is induced in the non-magnetic electrically conductive material thereof of effecting longitudinal propulsion of the shuttle through the coaction of said induced current with a traveling magnetic field.

41. A loom provided with electro-dynamic means comprising a coil-carrying core section and a return core section separated by a narrow longitudinal air gap and energized by a polyphase alternating current and acting to induce current within an electrically conductive filling carrier extending into and movable in said air gap, the said means coacting with said induced current to project the filling carrier along the gap and out of said gap and thence across the loom and the said core sections projecting equally toward the center of the loom a substantial distance beyond the coils to minimize distortion of the paths of the flux generated by the end coils thus to insure the projection of the filling carrier from the air gap at maximum speed.

42. A loom provided with electro-dynamic

means comprising a coil-carrying core section and a return core section separated by a narrow longitudinal air gap and energized by a polyphase electric current, a filling carrier having a thin fin of electrically conductive material movable within and extending at both sides of the air gap, the said means acting to induce current within the fin and coacting with said induced current to project the filling carrier along and out of said air gap and across the loom and the extensions of the fin at both sides of the air gap acting to provide return paths for eddy currents induced therein and thus increase the efficiency of operation.

43. A loom provided with electro-dynamic means comprising a magnetic system having two parallel core sections spaced a short distance apart to form a narrow longitudinal air gap, a polyphase coil winding on the core, and an electrically conductive filling carrier having a thin fin fitting the said air gap, the said apparatus acting to produce a maximum electro-dynamic force upon the fin with a minimum number of ampere turns in the coils when the said coils are energized by a polyphase alternating current.

44. A loom provided with an electro-dynamic apparatus for initiating and accelerating the movement of a filling carrier across the loom comprising a two-section core of rectilinear form, the sections thereof being held in parallel spaced relation to form an air gap, electro-magnetic means acting to produce a magnetic field within the core passing transversely of said air gap and of varying intensity with its point of maximum density traveling longitudinally of the core, a filling carrier having a fin fitting the air gap and having one or more paths of high magnetic conductivity and also comprising non-magnetic electrically conductive material presenting paths for induced currents whereby when said electro-magnetic means is energized a force will be created acting upon the fin to move it longitudinally of the core while within the field and having a minimum decelerating influence thereon as it leaves the field under its own momentum.

45. An electro-dynamic apparatus for initiating and accelerating in opposite directions the movements of an electrically conductive body in a defined terminated path comprising an electro-magnetic system having core sections at opposite sides of said path held in closely spaced relation to form a narrow air gap, the core section or sections at one side of the air gap carrying exciting coils, the core section or sections at the opposite side of the air gap constituting a return path for the magnetic flux, a thin non-magnetic electrically conductive body fitting the air gap, means for connecting a polyphase alternating current to said coils, and means for periodically shifting the connection of said current to cause a unidirectional force to act upon the thin non-magnetic electrically conductive body within the air gap and cause it to reciprocate in the air gap.

EDWARD L. BOWLES.
